A. W. NELSON.
SASH SUPPORTER,
APPLICATION FILED FEB. 16, 1914.

1,127,666.

Patented Feb. 9, 1915.

UNITED STATES PATENT OFFICE.

ARTHUR W. NELSON, OF WILLIAMSPORT, PENNSYLVANIA.

SASH-SUPPORTER.

1,127,666.

Specification of Letters Patent.

Patented Feb. 9, 1915.

Application filed February 16, 1914. Serial No. 818,956.

To all whom it may concern:

Be it known that I, ARTHUR W. NELSON, a citizen of the United States, residing at Williamsport, in the county of Lycoming and State of Pennsylvania, have invented 5 certain new and useful Improvements in Sash-Supporters; and I do declare the following to be a full, clear, and exact description of the invention, such as will enable 10 others skilled in the art to which it appertains to make and use the same.

This invention relates to improvements in means for supporting window sash and the main object of the same is to devise an article 15 of the character described which will obviate the necessity of employing weights to retain the sash in raised position.

To this end, a second object is to construct the device in such a manner that it will 20 allow the window to be easily raised, but will effectually retard its descent.

With the above objects in view, the invention resides in certain novel features of construction and combination herein described 25 and claimed and shown in the drawings wherein:

Figure 1 is an inside elevation of a portion of a window sash and frame showing the application of my invention thereto; Figs. 2 30 and 3 are edge views of the opposite edges of the sash showing the location of parts thereon; Fig. 4 is a detail horizontal section on the line 4—4 of Fig. 1; Fig. 5 is a detail vertical section showing the manner of 35 mounting the supporting rollers; and Fig. 6 is a side elevation of one of the attaching plates on an enlarged scale.

In the accompanying drawings, I have shown a window frame F comprising the 40 usual sill S, parting strips P, and sash retaining strips s and a sash S' which is slidably mounted within said frame and between the strips P and s in the usual manner. The opposite sides of the sash S' are 45 channeled vertically as shown at 1 for a purpose to appear.

Secured near the top and bottom of one of the channels 1 is a pair of supporting devices which comprise attaching plates 2 having 50 ears 3 projecting outwardly from their opposite edges, said plates 2 being secured to the side bars of the sash by means of screws 4. The ears 3 on one side of the plates 2 are provided with upright slits 5 while the ears on the other sides thereof are 55 provided with circular bearing openings 6

which are disposed in horizontal alinement with the lower ends of the slots 5. Revolvably mounted between the ears 3 and having their pintles 7 projecting into the slots 5 and bearing openings 6 are sash supporting 60 rollers 8 which as shown, preferably have their peripheries of less length than their central portions.

Located within the channel 1 at the opposite side of the sash S', are upper and lower attaching plates 9 which have bearing ears 10 projecting outwardly from their opposite edges, said plates being rigidly secured at 11 to the opposite ends of a flat 70 leaf spring 12 which is bent in such a manner as to provide a contact point 13 at its center, said point normally contacting with the edge of one side bar of the sash. The ears 10 on one edge of the attaching plates 9 75 are provided with upright slots 14, while the ears on the other sides thereof have circular bearing openings 15 which are disposed in horizontal alinement with the lower ends of said slots, said slots and openings being 80 provided for the reception of bearing pintles 16 which project from the opposite ends of supporting rollers 17 which are located between said ears, and are adapted for a purpose to appear. For the purpose of retaining 85 the spring 12 and the parts carried by the opposite ends thereof in proper position, I provide fastening screws 18 which project loosely through openings 19 near the opposite ends of said spring and enter the edge of 90 the sash. It may here be stated that the rollers 8 and 17 are normally held in contact with the opposite inner sides of the frame E through the tension of the spring 12.

With the parts as above described, when 95 the sash S' is raised, the pintles of the various rollers will assume horizontal positions and will thus allow the sash to be readily raised. When, however, the sash is released, its own weight will cause the ends of the 100 pintles which are journaled in the bearing openings 6 and 15 to move downwardly, thus inclining said rollers and causing their direction of rotation to move the entire sash toward the parting strips P with which it 105 will frictionally contact, thus retaining the sash in any one of its raised positions. The frictional contact between said sash and parting strips is not great enough, however, to prevent the sash from being lowered by 110 force. Thus it will be seen that I have provided an extremely simple and efficient sash

supporter which will retain the sash in any one of its raised positions, but which will allow said sash to be easily raised.

Although I have described my invention as applied to a window sash movable within the usual frame, it will be understood that I need not be limited to this application, since the device would operate to equal advantage in connection with any fixed 10 guide and movable member.

Having thus described my invention, what I claim as new and desire to secure by Letters-Patent is:—

1. The combination with a fixed guide and a movable member slidable against the same, of a roller carried by said member and in contact with said guide one end of said roller being mounted to move in a plane transverse to its axis.
2. The combination with a fixed guide and a movable member slidable against the same, of an attaching plate carried by said member, bearing ears on the opposite sides of said plate, one of the ears having a bearing slot and the other ear having a circular bearing opening, a roller having pintles mounted in said bearing slot and opening and means for causing said roller to contact with the guide.
3. The combination with a window frame having upright guide strips and a sash vertically movable between said strips and having its opposite edges channeled, of attaching plates within said channels, bearing ears

on said plates, one of the ears on each plate 35 having an upright slot and the remaining ears having circular bearing openings in horizontal alinement with the lower ends of said slots, and rollers between said ears and having pintles revolvably mounted in said 40 slots and circular bearing openings, said rollers being in contact with said window frame, whereby the weight of the sash, when raised will cant the rollers and cause said sash to frictionally contact with said upright strips.

4. The combination with a guide and a member movable in respect thereto, of a strip of spring metal having a contact point substantially at its center, attaching plates 50 secured to the opposite ends of said strip, ears on the opposite sides of said attaching plates, one of said ears on each plate having a bearing slot and the remaining ears having circular bearing openings, rollers between said ears and having pintles projecting into said slots and bearing openings, and retaining screws passing loosely through said metal strip and into said movable member.

In testimony whereof I have hereunto set my hand in presence of two subscribing witnesses.

ARTHUR W. NELSON.
